CONTROLLING MECHANISM

Frank E. Sinclair, Claremont, N. H., assignor to
 Sullivan Machinery Company, a corporation of
 Massachusetts

Application July 23, 1940, Serial No. 346,938

11 Claims. (Cl. 121—9)

My invention relates to controlling mechanism, and more particularly to improved feed controlling mechanism for pneumatically fed devices such as so-called air-feed drifters.

In the operation of air-feed drifters, which are hammer motors fed along suitable guiding and supporting means by air motors, which ordinarily, though not necessarily, rotate the feed screw element of a feed screw and nut to effect feed and retraction of the hammer motor, it is desirable to have the rate of forward feed—basically, the feeding pressure—controllable with considerable nicety, but at the same time to be able to drive the feeding motor at will at full speed in either direction substantially instantly. It is also desirable to be able to resume a pre-selected controlled rate of air supply to the feeding motor at will at any time simply by moving the feed control lever into a selected position. Accordingly, an arrangement in which a main valve is movable into opposite extreme positions to effect full forward feed in one position and full speed retraction in the other such position, and is movable into an intermediate position to effect a predetermined reduced rate of motive fluid supply to the motor to effect forward feed, is highly desirable; and it is further desirable to be able to regulate the reduced rate of air supply at will at any time. In a preferred embodiment of my invention, therefore, there may be incorporated a main reversing valve having three predetermined positions, respectively, one for full forward feed, one for full speed retraction, and an intermediate one for reduced forward feed; and with said main valve there may be desirably associated an auxiliary valve adjustable relative to the main valve to vary the rate of feeding pressure supply through the latter when the main valve is in the intermediate position, but having no effect upon the rate of fluid supply when the main valve is in either of its extreme positions. Desirably, the auxiliary valve may be arranged within the main valve and may be adjustable relative to the latter not only to regulate the rate of fluid supply by throttling but also by a concurrent partial venting of the fluid before it reaches the feed operating motor. Desirably, both valves may be of the rotatable type and a coaxial arrangement of the valves will be, under such circumstances, of advantage. It will be appreciated, however, that the several arrangements outlined, while preferred, are not requisite, and that the invention is capable of wide variation within the scope of the appended claims.

It is an object of my invention to provide an 55

improved pressure controlling mechanism. It is another object of my invention to provide an improved controlling mechanism for a pneumatic feeding mechanism. It is a further object of my invention to provide an improved controlling mechanism for a pneumatically operated reversible feed mechanism. It is still another object of my invention to provide an improved controlling mechanism for a pneumatic reversible feed mechanism, having incorporated therein improved means for providing a sub-maximum feeding rate which may be resorted to at any time, together with higher speed forward and reverse feed rates each of which may be instantly adopted. Still another object of my invention is to provide an improved mechanism of the character described having improved means for adjusting the sub-maximum feed rate. Yet a further object of my invention is to provide an improved feed controlling mechanism including concurrently movable reverse and feed rate controlling valves, the second adjustable relative to the first to vary the feeding rate and the first movable to supply motive fluid either under the control of the second or independently thereof at a higher rate. Another object of my invention is to provide an improved pneumatic feed controlling mechanism including a valve movable to effect feed in either of opposite directions and having a plurality of fluid supply passages selectively effective to provide feed in one direction, with means for controlling the rate of supply through one; but not the other, of said passages. Other objects and advantages of my invention will hereinafter more fully appear.

In the accompanying drawings, in which one form of the invention is shown for purposes of illustration:

Fig. 1 is a side elevation of an air-feed dritter in which my invention in its illustrative embodiment is incorporated.

Fig. 2 is an enlarged rear end view of the apparatus shown in Fig. 1.

Fig. 3 is an enlarged sectional view taken on the planes of the section line 3—3 of Fig. 2.

Fig. 4 is an enlarged cross sectional view taken on the planes of the line 4—4 of Fig. 3.

Fig. 5 is an enlarged transverse sectional view through a controlling valve mechanism, on the plane of the line 5—5 of Fig. 3.

Fig. 6 is a side elevational view of a main feed reversing valve, with its operating handle removed.

Fig. 7 is an elevational view of a feed rate

controlling valve, with its operating handle removed.

Figs. 8, 9, 10, 11 and 12 are enlarged sectional views of the controlling valve mechanism, and are taken respectively on the transverse planes of the section lines 8—8, 9—9, 10—10, 11—11 and 12—12 of Fig. 3.

Referring now to the drawings, it will be observed that a hammer motor, generally designated 1, adapted percussively to actuate a drill steel 2, is slidably guided in a shell 3 having a trunnion support 4. The hammer motor carries a feed nut, a portion of which is shown at 5 in Fig. 1, and this feed nut is threadedly interengaged with a feed screw 6 which extends longitudinally of the shell 3 and is rotatably supported thereby in a well known manner. The feed screw 6 may be rotated by any suitable pressure fluid operated motor, and herein for that purpose I have shown in elevation a four-cylinder reversible air motor, generally designated 7, having cylinders 8, 8', 8'', 8''''. The details of this motor need not be gone into herein as they per se form no part of my present invention, and it will suffice to say that the motor 7 is a reversible motor, a portion of the exhaust from which, irrespective of the direction of rotation, is discharged back through the passage to which motive fluid is supplied when the motor is operating in the opposite direction. It should be said at this point that in its broader phases my invention is not limited to the provision of exhaust facilities in the control mechanism, but that in the embodiment shown for purposes of illustration this feature is incorporated.

The motor 7 has leading to it two passages 11 and 12. Supply of fluid through the passage 11 (attended in this case by concurrent exhausting of fluid through the passage 12) will effect forward feed of the hammer motor 1. Supply of fluid through the passage 12 (attended in this case by exhaust of fluid through the passage 11) will effect retraction of the hammer motor 1. The passages 11 and 12 are formed in a valve casing 13, herein supported on the body of the feed operating motor 7. The valve casing 13 is provided with a cylindrical bore 14, herein of uniform diameter throughout its length, and the bore is closed at one end by a head 15 to which a suitable supply connection 16 for operating fluid is attached, as by a coupling 17. The opposite end of the casing has an opening 18 therethrough through which the stem 20 of a reversing and feed controlling valve 21 extends. The feed controlling valve 21 has, at the outer end of its stem, a fixture 22 supporting an operating handle 23.

The feed controlling valve 21 is hollow throughout its length and at its end nearer the supply connection 16 has a bore 25 formed therein which opens through the right-hand end (in Fig. 3) of the valve. The bore 25 communicates with a slightly smaller bore 26, and to the left (in Fig. 3) of the bore 26 is a still smaller bore 27 which extends completely through the valve member 21 and its stem 20. Within the bore 26 there is mounted a valve element 29 which has an elongated operating portion 30 extending through the bore 27, and fixed on the outer end of the portion 30 is a handle 31 by means of which the valve 29 can be rotated. The handle 31 carries a pin 32 which is movable in an arcuate opening 33 formed in the outer end of the valve stem 20, the purpose of this pin and slot connection being to limit the movement of the valve 29 relative to the valve 21.

In the valve 21, in the same transverse plane with the passage 12, is a radial port 35 communicating with the bore 25 and adapted to supply fluid, in the proper position of the valve 21, to the passage 12. The valve 21 is also provided with a longitudinally extending groove 37 in its periphery, and this groove is connected by passages 38 and 39 with the bore 26. The position of the groove 37 is such that its right-hand end in Fig. 3 is communicable, in the shown position of the valve 21, with the passage 11. The valve 21 also has a radial passage 40 therein, in the same transverse planes with the passage 11, the passage 40 being offset arcuately of the valve 21 from the groove 37. The valve 29 has a bore 42 therein opening into communication with the bore 25. The valve 29 has a radially extending passage 43 connecting the bore 42 with a lune-shaped peripheral groove 44. The valve 29 also has another lune-shaped groove in its periphery at 45, the latter in the same transverse planes with the radial port 39 in the valve 21. The valve 21 has another radial passage 46 therein, the radial passage 46 opening into an exhaust groove 47 which extends longitudinally of the valve 21 and communicates at its left-hand end in Fig. 3 with a peripherally extending exhaust groove 48 of more than 180° extent, as shown in Fig. 8. In the transverse planes of the exhaust groove 48 there are provided exhaust passages 49 opening through the wall of the valve casing 13. The groove 47 extends to the right in Fig. 3 to a point opposite passage 12, and formed in the valve 21 is a peripherally extending groove 50 opening at one end into the groove 47. Approximately opposite the exhaust groove 47 is another longitudinally extending exhaust groove 51 which extends to the left in Fig. 3 substantially the same distance as the left-hand end of the peripheral groove 48; and to the right in Fig. 3 extends to a point opposite the end of the passage 11. It may be observed with respect to the lune-shaped grooves 44 and 45 that these are so related to each other and to the ports with which they are communicable that the groove 44 may be in full communication with the passage 38, while there is no communication between the groove 45 and the passage 46; but that by rotation of the valve 29 clockwise from the position initially described to the position shown in Figs. 9 and 10 there may be a concurrent connection of the groove 44 with the passage 38 and of the groove 45 with the passages 39 and 46 at the same time. It will be noted that on still further rotation in a clockwise direction the communication of the groove 44 with the passage 38 may be diminished or entirely discontinued, if desired, without interrupting the communication between the port 39 and the port 46. Since the port 38 receives fluid from the groove 44 through the port 43 and bore 42, and since the port 39 may be connected through the groove 45 to the port 46, the exhaust grooves 47 and 48 and the exhaust ports 49, with the atmosphere, it will be evident that the net quantity of fluid deliverable from the groove 37 with which the ports 38 and 39 both communicate may be closely controlled and be anything from the maximum flow capacity of the port 43 down to zero.

A spring locking plunger 52 reciprocable in a bore 53 in the casing 13 is adapted to cooperate with either of two recesses 54 and 55 in the valve stem 20. The fixture 22 has a projecting boss thereon, as indicated in Fig. 4 at 56, said boss having oppositely facing surfaces 57 and 58. The surfaces 57 and 58 respectively coact, in the op-

posite extreme positions of the lever 23, with surfaces 59 and 60 on the valve casing 13. When the surface 57 engages the surface 59 the port 40 will be in full communication with the passage 11 and the groove 50 will be in communication with the passage 12. When the handle 23 is moved clockwise in Fig. 4 far enough to bring the notch 54 opposite the plunger 52, the groove 37 will be opposite the passage 11 and the groove 50 will still be opposite passage 12. Further clockwise movement of the handle 23 bringing the notch 55 opposite the plunger 52 will bring the blank surface 61 on the periphery of the valve 21 opposite the passages 11 and 12. Still further clockwise movement of the handle 23 in Fig. 4 will bring the surface 58 against the shoulder 60, and in this position of the valve 21 the port 35 will be opposite the passage 12. When the port 35 is opposite the passage 12, the passage 11 will be connected by the longitudinal groove 51 with the exhaust ports 49. When the groove 37 is in communication with the passage 11, the passage 12 will be connected by the groove 50 with the groove 47 and through the groove 48 with the exhaust 49. When the port 40 is in communication with the passage 11, the groove 50 and grooves 47 and 48 will connect the passage 12 with the exhaust 49.

The mode of operation of the apparatus described will be clearly apparent from what has been said. The operation may be summarized once more, however, to provide a complete description of the operation at one place. Rotation of the handle 31 relative to the handle 23 will turn the valve 29 within the valve 21 and position the lune-shaped grooves 44 and 45 in such a manner that the desired net quantity of fluid may be delivered from the groove 37 to effect the reduced or controlled rate of forward feed desired. Turning the valve 29 clockwise in Figs. 9 and 10 will reduce the rate of feed; turning it counterclockwise will increase the rate of feed.

Now starting with the valve 21 in a position with the plunger 52 engaged in the recess 55, it will be observed that the passages 11 and 12 will both be blanked off by the periphery of the valve 21. If the drill motor 1 is at the back end of the guide shell 3 and it is necessary to feed the motor 1 forward some little distance to bring the steel 2 into operative relation to the work, the handle 23 will be thrown counterclockwise to bring the surface 57 against the shoulder 59. This will bring port 40 into communication with the passage 11 and concurrently will establish communication of the passage 12 through the grooves 50, 47 and 48 with the exhaust passages 49, and full speed forward feed will take place. When the steel approaches the work, the operator may move the handle 23 clockwise to bring the notch 54 opposite the plunger 52, and this will locate the slot 37 opposite the port 11 while maintaining communication of the passage 12 through the grooves 50, 47 and 48 with the exhaust 49. The rate of motive fluid supply to the feed motor 1 will then be dependent upon the position of the valve 29 relative to the valve 21, and may be adjusted at will simply by rotating the valve 29 through the handle 31. When the operator desires to effect reverse feed he will move the handle 23 clockwise to the extreme position permitted, and that will bring the port 35 opposite the passage 12 and supply fluid to effect reverse feed, and the passage 11 will then be connected through the slot 51 and passages 49 to exhaust. Obviously, the operator can mo-

mentarily hold the valve 21 in various intermediate positions and at will determine the quantities of fluid which can flow through the passage 35 or the passage 40.

From the foregoing description it will be obvious that I have provided an improved control mechanism having improved, simple and positive arrangements for permitting full speed feed in either direction and shutting down the feeding motor entirely, or a forward feed at a rate which may be varied at the will of the operator by the adjustment of the valve 29 relative to the valve 21. The parts are compactly arranged, and complicated passage arrangements are avoided, and any desired mode of operation of the feeding motor within the capacity of the latter can be obtained.

While I have in this application specifically described one embodiment which my invention may assume in practice, it will be understood that this form of the same is shown for purposes of illustration only and that the invention may be modified and embodied in various other forms without departing from its spirit or the scope of the appended claims.

What I claim as new and desire to secure by Letters Patent is:

1. In a valve mechanism, in combination, a valve casing, a pair of ports opening into said casing, means including an adjustable valve operative in one position for connecting said ports respectively to pressure fluid supply and exhaust and operative in another position for reversing the connections to said ports, and means for regulating the amount of pressure fluid flowing to one of said ports when said valve is in one of its positions including means for establishing a communication and adjustably controlling the communication of said latter port with exhaust.

2. In a valve mechanism, in combination, a valve casing, a pair of ports opening into said valve casing, means including an adjustable valve operative in one limiting position for connecting said ports respectively to pressure fluid supply and to exhaust and operative in an opposite limiting position for reversing the connections to said ports, said valve being movable to an intermediate position for supplying pressure fluid to one of said ports, and valve means adjustable relative to said valve for varying at will the flow of pressure fluid past said valve to the latter one of said ports when said valve is in said intermediate position.

3. In a valve mechanism, in combination, a valve casing, a pair of ports opening into said valve casing, means including an adjustable valve operative in one position for connecting said ports respectively to pressure fluid supply and to exhaust and operative in another position for reversing the connections to said ports, said valve being operative in still another position for effecting a fluid supply to one of said ports, and adjustable valve means for controlling the supply of fluid to the last mentioned one of said ports when said valve is in its last mentioned position.

4. In a valve mechanism, in combination, a valve casing, ports opening into said valve casing, means including an adjustable valve for controlling the connection of said ports to supply and exhaust, and means operative in one position of said adjustable valve for connecting one of said ports simultaneously to fluid supply and exhaust.

5. In a valve mechanism, in combination, a

valve casing, ports opening into said valve casing, means including an adjustable valve for controlling the connection of said ports to supply and exhaust, and means including valve means operative in one position of said adjustable valve for connecting one of said ports to fluid supply and exhaust, said valve means being operative for controlling simultaneously the supply and exhaust connections to said latter port.

6. In a valve mechanism, in combination, a valve casing, a pair of ports opening into said valve casing, and means for selectively supplying fluid to one of said ports and exhausting fluid from the other including a valve having spaced supply passages one for coaction with one of said ports and the other for coaction with the other of said ports, and also exhaust means for exhausting fluid from said ports one at a time, said valve having a further supply passage for supplying fluid to one of said ports.

7. In a valve mechanism, in combination, a valve casing, a pair of ports opening into said valve casing, and means for selectively supplying fluid to one of said ports and exhausting fluid from the other including a valve having spaced supply passages one for coaction with one of said ports and the other for coaction with the other of said ports, and also exhaust means for exhausting fluid from said ports one at a time, said valve having a further supply passage for supplying fluid to one of said ports, and said valve having within the same another valve controlling the supply of fluid to said further supply passage.

8. In a valve mechanism, in combination, a valve casing, a pair of ports opening into said valve casing, and means for selectively supplying fluid to one of said ports and exhausting fluid from the other including a valve having spaced supply passages one for coaction with one of said ports and the other for coaction with the other of said ports, and also exhaust means for exhausting fluid from said ports one at a time, said valve having a further supply passage for supplying fluid to one of said ports, and said

valve having coaxial therewith and rotatable relative to the same another valve controlling the supply of fluid to said further supply passage.

9. In a valve mechanism, in combination, a valve casing, a pair of ports opening into said valve casing, and means for selectively supplying fluid to one of said ports and exhausting fluid from the other including a valve having spaced supply passages one for coaction with one of said ports and the other for coaction with the other of said ports, and also exhaust means for exhausting fluid from said ports one at a time, said valve having a further supply passage for supplying fluid to one of said ports, and said valve having within the same another valve currently controlling the supply and venting of fluid to regulate the pressure delivered to said further supply passage.

10. In a valve mechanism, in combination, a valve casing, a plurality of ports opening into said valve casing, and means for selectively supplying and exhausting fluid relative to said ports including a valve having spaced supply passages one for coaction with one of said ports and another for coaction with another of said ports, and also exhaust means for exhausting fluid from said ports one at a time, said valve having a further supply passage for supplying fluid to one of said ports, and means for controlling the fluid pressure delivered to the last mentioned one of said ports from said further supply passage including an adjustable valve controlling the communication of said port with exhaust.

11. In a valve mechanism, in combination, a valve casing, a port opening into said valve casing, and means including valve means for connecting said port simultaneously to pressure fluid supply and to exhaust, said valve means controlling simultaneously the supply and exhaust connections to said port and operative to effect a change in the flow of pressure fluid to exhaust in inverse proportion to the change in the flow of pressure fluid from said supply.
